(57) **CLAIM**

The ornamental design for a cutting board as shown and described.

DESCRIPTION

FIG. 1 is a top perspective view of a cutting board, showing our new design;

FIG. 2 is a bottom perspective view of the cutting board of FIG. 1;

FIG. 3 is a top plan view of the cutting board of FIG. 1 which is the same as the bottom plan view;

FIG. 4 is a front elevation of the cutting board of FIG. 1 which is a mirror image of the rear elevation;

FIG. 5 is a side elevation of the cutting board of FIG. 1 which is a mirror image of the opposite side elevation; and, FIG. 6 is a cross section view taken along line 6-6 of FIG. 3.

The broken lines are shown for the purpose of illustrating parts of the article that form no part of the claimed design.

1 Claim, 4 Drawing Sheets
